I. M. MARKS

ELECTRIC GRATE

Filed April 19, 1927

Inventor:
Irving M. Marks
Dyungforth & Clinton-Wiles

Patented July 5, 1927.

Des. 73,006

UNITED STATES PATENT OFFICE.

IRVING M. MARKS, OF CHICAGO, ILLINOIS.

DESIGN FOR AN ELECTRIC GRATE.

Application filed April 19, 1927. Serial No. 21,642. Term of patent 3½ years.

To all whom it may concern:

Be it known that I, IRVING M. MARKS, a citizen of the United States, residing at Chicago, county of Cook, and State of Illinois, have invented a new, original, and ornamental Design for an Electric Grate, of which the following is a specification, reference being had to the accompanying draw-

ing, forming a part hereof, in which the single figure is a perspective view of the article, showing my new design.

I claim:

The ornamental design for an electric grate as shown.

IRVING M. MARKS.
